UNITED STATES PATENT OFFICE.

ASHLEY D. SCOTT, OF ST. LOUIS, MISSOURI.

DESIGN FOR AN ELECTRODE.

SPECIFICATION forming part of Design No. 31,495, dated September 5, 1899.

Application filed August 10, 1899. Serial No. 726,837. Term of patent 14 years.

To all whom it may concern:

Be it known that I, ASHLEY D. SCOTT, a citizen of the United States, and a resident of the city of St. Louis, State of Missouri, have 5 invented and produced a new and original Design for Electrodes, of which the following is a specification, reference being had to the accompanying drawings, forming part thereof.

Figure I is a perspective view of an electrode, showing my new design. Fig. II is a 10 transverse section taken on line II II of Fig. I.

As shown in the drawings, the leading or material feature of my design consists of a

series of ribs 1, divided or separated by longitudinal body portions 2. At the upper end 15 of the body portion there is a ribless or smooth portion 3, surmounted by a neck 4.

Having described my invention, what I claim as new, and desire to secure by Letters Patent, is—

The design for an electrode as herein shown and described.

ASHLEY D. SCOTT.

In presence of—

E. S. KNIGHT,

M. P. SMITH.
